UNITED STATES PATENT OFFICE.

JOSEPH GOODMAN, OF WHITNEYVILLE, CONNECTICUT, ASSIGNOR TO THE MT. CARMEL MANUFACTURING COMPANY, OF MOUNT CARMEL, CONNECTICUT, A CORPORATION OF CONNECTICUT.

DESIGN FOR A VEHICLE-DOOR HANDLE.

Application filed March 29, 1923. Serial No. 5,635. Term of patent 7 years.

To all whom it may concern:

Be it known that I, JOSEPH GOODMAN, a citizen of the United States, residing at Whitneyville, county of New Haven, State of Connecticut, have invented new, original, and ornamental Design for Vehicle Door Handles, of which the following is a specification, reference being had to the accompanying drawing, forming part thereof.

Fig. 1 is a front elevation of a vehicle door handle, showing my new design.

Fig. 2 is a side elevation thereof, and Fig. 3 is a top plan view of the same.

In Figures 1 and 3 the central shaded strip down the front of the handle indicates an insert of a different material and color from the body of the handle.

I claim:

The ornamental design for a vehicle door handle, substantially as shown and described.

JOSEPH GOODMAN.
